DESIGN FOR AN ICE CREAM DISPENSING CABINET OR SIMILAR ARTICLE

Elliott H. Helms, Los Angeles, Calif.

Application October 31, 1939, Serial No. 87,958

Term of patent 7 years

To all whom it may concern:

Be it known that I, Elliott H. Helms, a citizen of the United States, residing at Los Angeles, in the county of Los Angeles, in the State of California, have invented a new, original, and ornamental Design for an Ice Cream Dispensing Cabinet or Similar Article, of which the following is a specification, reference being had to the accompanying drawing forming a part thereof.

I claim:

The ornamental design for an ice cream dispensing cabinet or similar article, substantially as shown.

ELLIOTT H. HELMS.
